ATTORNEY

UNITED STATES PATENT OFFICE.

CALVIN R. WAID, OF BIRMINGHAM, ALABAMA.

SELF-OPENING TRAVELING BAG.

1,413,079.

Specification of Letters Patent. Patented Apr. 18, 1922.

Application filed October 18, 1920. Serial No. 417,797.

To all whom it may concern:

Be it known that I, CALVIN R. WAID, a citizen of the United States of America, residing at Birmingham, in the county of Jefferson and State of Alabama, have invented 5 certain new and useful Improvements in a Self-Opening Traveling Bag, of which the following is a specification.

My invention relates to an improvement 10 in satchels, hand bags and grips which open at the top, and my object is to dispense with the present style of hinges as used and to substitute therefor a very simple, cheap and effective spring connection which will not 15 only take the place of the hinge but will also serve the valuable purpose of opening and holding open the top of the bag.

The convenience in packing and unpacking 20 a bag, the top of which will be held open, is obvious and I propose to attain this end without increased cost or in any way impairing the usefulness or desirability of the bag. Moreover the provision of a hinge of this type prevents the bag being carried 25 or left unlatched, which often causes the loss of articles therefrom.

My invention, in its preferred embodiment only, will be best understood by reference to the accompanying drawings which 30 form a part of this specification, and in which:—

Fig. 1 shows a hand bag in partially open 35 position to illustrate the spring in end elevation.

Fig. 2 shows the bag as fully opened by the spring latch which is here shown opened out to its position of rest.

Fig. 3 is a plan view of the spring hinge 40 as shown in Fig. 2.

Similar reference numerals refer to similar parts throughout the drawings.

I have illustrated my invention as applied to a hand bag 1 which is typical of any satchel, grip, or traveling bag that opens at 45 the top. The top has attached thereto the usual marginal metallic frames 2 which comprise inner and outer metal bars 3 and 4, respectively. These bars grip between them the lining for the bag and also carry the 50 customary top lock and latch members and handle 6. All this part of the construction

illustrated is purely formal as it may vary in different types and makes of traveling bags.

The frames 2, as at present made, are 55 provided at their meeting ends with hinge lugs which are hingedly connected by hinge pins or rivets, but it is my intention to dispense with this type of connection and to substitute therefor the spring hinge which 60 comprises a central bow 7 and flat ends 8 which are shown as interposed between the adjacent ends of the inner and outer bars 3 and 4 and are held in position between them by the rivets 9. The bow is of such 65 shape and size as to be free to expand in the fold 10 which is provided at each side of the top opening and the spring is of such design and character as to offer no 70 serious resistance to the closing of the bag but to have sufficient strength, upon unlatching the bag, to open it out to the position shown in Fig. 2 or any intermediate 75 position, as shown in Fig. 1, and hold it there. Any suitable spring metal or flexible 80 hinge straps may be utilized to carry out the operation as above described and when so applied it will be obvious that the bag 85 will naturally and automatically open its top the moment it is unlatched and will hold the top open in the most convenient position for the packing and unpacking of the bag.

The springs are very simple and inexpensive, can be applied without appreciable 90 cost, and will take the place of the hinges while affording the additional advantages above defined.

Having thus described my invention, what I claim as new and desire to secure by Letters Patent, is:—

1. A traveling bag adapted to open at the top and comprising top marginal frames carrying suitable handle and latch means, and being hingedly connected by a spring 95 which tends to open the bag when unlatched.

2. A traveling bag adapted to open at the top and comprising top marginal frames, latch means for the frames, and a spring 100 at each end of the bag which serves to hingedly connect said marginal frames

and to open the bag when the frames are unlatched.

3. A traveling bag adapted to open at the top and comprising a pair of outwardly opening top frames, a latch means for said frames, and flat springs, each provided with an intermediate bow which serve both as

the hinge connections for said frames and as spring means to automatically open the bag when said frames are unlatched.

10

In testimony whereof I affix my signature.

CALVIN R. WAID.
